UNITED STATES PATENT OFFICE.

WILLIAM L. BELL, OF SANTA CRUZ, CALIFORNIA.

SURGICAL INSTRUMENT FOR TOTAL HYSTERECTOMY.

1,292,998.

Specification of Letters Patent.

Patented Feb. 4, 1919.

Application filed June 14, 1917. Serial No. 174,714.

To all whom it may concern:

Be it known that I, WILLIAM L. BELL, a citizen of the United States, and a resident of the city and county of Santa Cruz, State 5 of California, has made a new and useful invention—to-wit, Surgical Instruments for Total Hysterectomy; and I do hereby declare the following to be a full, clear, concise, and exact description of the same.

10 This invention relates particularly to instruments for accomplishing a complete abdominal hysterectomy, with the particular object of expediting such operations eliminating the necessity for multiplying the 15 number of clamps, tenacula and like instruments; minimizing hemorrhage, and other objects as will appear as this description progresses.

In this specification and the annexed 20 drawings the invention is illustrated in the form considered to be the best, but it is to be understood that the invention is not limited to such form, because it may be embodied in other forms and it is also to be understood 25 that in and by the claims following the description it is desired to cover the invention in whatever form it may be embodied.

In the accompanying one sheet of drawings:

30 Figure 1 is a side elevation of an instrument constructed in accordance with this invention, partially broken away to disclose underlying structures.

Fig. 2 is a side elevation of the detached 35 tubular cutting-blade.

Fig. 3 is fragmentary detail of a modified sheath end.

In detail the structure illustrated in the drawings includes:

40 A tubular sheath 1 having a rounded and polished upper edge 2. This sheath is provided with the annular shoulder or bead 3 spaced backward from the edge 2. An annular groove may be substituted for the bead 45

3. This sheath incloses the tubular blade 4 fitting snugly therein, the lower edge 5 of the sheath being chamfered to facilitate assembling the blade 4 within the sheath. The blade is provided with a threaded opening 6 registering with an unthreaded opening 7 in the sheath 1, to receive the set-screw 8 provided with a knurled head 9 to clamp the blade in fixed relation to the sheath. The cutting edge 10 of the blade, when fixed with 55 in the sheath by the set-screw, is spaced backward a distance from the edge 2 of the

sheath. The opposite end 10 of the blade projects a convenient length beyond the end 5 of the sheath, to provide a hand-grip for manipulating the blade. When the instrument is to be used in severing the uterus, the set-screw 8 is removed and the blade 4 rotatively advanced until the cutting edge 9 extends beyond the edge 2 of the sheath, limited by the abutment of the stud 12 60 against the end 5 of the sheath. To facilitate bringing the opening 6 into registry with the set-screw 8 the blade 4 is marked with an index as at 13 registering with a notch in the end 5 of the sheath in alinement 65 with the screw 8.

This instrument is operated substantially as follows:

The patient is prepared in the routine manner and placed in proper position on 75 the operating table.

First: Proper size sheath 1 is chosen and inserted into the vagina preceding incision. The sheath must be the proper size to receive the cervix within the end and should 80 be well lubricated and inserted gently until the cervix is encountered.

Second: The incision is made, the walls retracted and bleeding points ligated. The uterus is then supported by the hand of the 85 operator while the tube is gently pressed upward. The cervix is now placed in the end of the tube if it is not already there. The uterus is now forced upward by the assistant, through the agency of the sheath 1 previously inserted, a heavy ligature is passed around the vagina near the bead 3, but far enough away from the end 2 of the tube to leave $\frac{1}{2}$ of an inch of tissue. A long clamp 90 is now placed on each broad ligament, reaching down as far as the sheath 1. To insure against the displacement of said ligature the head of the sheath may be tapered toward the bead 3 as illustrated in Fig. 3. It is now clear that all blood supply to the uterus is 95

completely interrupted. The sheath 1, with the blade 4 inserted is brought upward until the vagina is encountered meantime the uterus being steadied from above by the hand of the operator. The blade 4 is now 100 rotated from without, until the vagina is accurately incised annularly at the cervix. Following the removal of the uterus in this manner it is evident that the vagina at the top of the stump remains dry, visible and 105 accessible and is held in place and visible by the sheath 1. The remaining steps are 110

routine surgery and it is deemed superfluous to describe the further details here.

Having thus described this invention, what I claim and desire to secure by Letters Patent is:

5. 1. A surgical instrument including a tubular sheath; an annular ligature guide on said sheath; a tubular cutting blade slideable in said sheath having the cutting edge projectable beyond one end of said sheath in operative position and the handle end of said cutting blade always beyond the other end of said sheath; means for retaining said blade in said sheath and means for limiting the projection of the cutting edge of said blade.
10. 2. A surgical instrument including a tubular sheath having an annular ligature guide thereon; and a tubular blade slideable in said sheath having the cutting edge projectable beyond one end of said sheath in
15. 3. A surgical instrument including a tubular sheath having a ligature guide thereon; a tubular blade the external diameter of which is less than the internal diameter of the sheath slideable in said sheath having the cutting edge projectable beyond one end of said sheath in operative position and the handle end of said cutting blade always beyond the other end of said sheath; and means for fixing said blade in said sheath.

operative position and the handle end of said cutting blade always beyond the other end of said sheath.

3. A surgical instrument including a tubular sheath having a ligature guide thereon; a tubular blade the external diameter of which is less than the internal diameter of the sheath slideable in said sheath having the cutting edge projectable beyond one end of said sheath in operative position and the handle end of said cutting blade always beyond the other end of said sheath; and means for fixing said blade in said sheath.

In testimony whereof, I have hereunto set my hand at San Francisco, California, this 4th day of June, 1917.

WILLIAM L. BELL.
